UNITED STATES PATENT OFFICE.

MARY GUYOT, OF CHICAGO, ILLINOIS.

DESIGN FOR A CHAIR.

SPECIFICATION forming part of Design No. 34,949, dated August 13, 1901.

Application filed July 12, 1901. Serial No. 68,117. Term of patent 7 years.

To all whom it may concern:

Be it known that I, MARY GUYOT, a citizen of the United States, residing at Chicago, in the county of Cook and State of Illinois, have 5 invented and produced a new and original Design for Chairs; and I do hereby declare the following to be a full, clear, and exact description of the same, reference being had to the accompanying drawings, forming a part 10 thereof.

This invention relates to a new and original design for chairs, and is illustrated in the accompanying drawings, in which—

Figure 1 is a front elevation of the chair, 15 and Fig. 2 is a side elevation thereof.

The seat of the chair is indicated at 6, the back at 7, and the legs at 8. The front legs are shorter than the rear legs, so that the seat inclines forwardly and downwardly. The 20 back of the chair inclines forwardly relative to a perpendicular rising from the point of junction of the back and the seat. At the

front edge of the seat a roll 9 is formed, projecting in a curve upwardly from the edge of the seat, then forwardly and downwardly 25 in semicylindrical form, extending longitudinally along the front edge of the seat with the convexity upward.

The essential features of the design are the downwardly and forwardly inclined seat, the 30 forwardly-inclined back, and the semicylindrical roll at the front edge of the seat.

Having thus described the invention, what is claimed as new, and desired to be secured by Letters Patent, is—

The design for a chair, as herein shown and described.

In testimony whereof I affix my signature in presence of two witnesses.

MARY GUYOT.
